UNITED STATES PATENT OFFICE.

EDWARD S. PRESTON, OF CHICAGO, ILLINOIS, ASSIGNOR, BY MESNE ASSIGNMENTS, TO CHICAGO ELECTRIC MANUFACTURING COMPANY, OF CHICAGO, ILLINOIS, A CORPORATION OF ILLINOIS.

INTERCONNECTED LAMP SOCKET.

Application filed July 23, 1923. Serial No. 653,106.

My invention relates to sockets for electric lamps and to circuit connections between them for enabling one lamp socket to provide detachable circuit connections for another socket also.

In one broad aspect, my invention aims to provide a lamp socket employing a substantially flat perforated supporting portion as the means for receiving and interlocking with the lamp base. For this purpose, my invention provides a construction which can readily be manufactured from sheet metal by a simple punch-press operation for serving as such a lamp support, which can readily be equipped with integral means for preventing an attached lamp from rocking, and which will permit another circuit connection to be secured to it in such a manner that the combination will afford an effective lamp-socket of unusually short length. Furthermore, my invention provides a socket construction of this class in which the conducting member employed for carrying the current to the axial contact of the lamp is so arranged that this conducting member can readily serve also as the means for conveying the current from a circuit terminal spaced from the socket.

In another broad aspect, my invention provides an arrangement of inter-connected lamp sockets which will permit one of the sockets to be used in combination with a wire-terminal plug for carrying the current from separate circuits to lamps associated both with that main socket and with another or auxiliary lamp-socket.

For this purpose, my invention provides a main socket equipped for holding a lamp having a single terminal at its rear end and for conveying current to this terminal from one terminal of a two-wire plug connected to that socket; it also provides conducting means arranged for receiving current from the other terminal of the plug and extending beyond the socket without interfering with the ready attaching of the lamp to that socket. Furthermore, it provides a twin socket construction for this purpose in which the said conducting means may also serve as a lamp-contacting portion of the companion or auxiliary socket, and provides simple means for suitably insulating the conducting means.

More particularly, my invention provides

a two-light socket assembly adapted for use with a pair of grounded circuits and so arranged that the two circuit wires can readily be connected to one of the sockets by means of an ordinary two-wire attaching plug, the last named socket being equipped both with means for carrying the current from one terminal of the plug to a lamp interlocked with that socket and for carrying current from the other terminal direct to the lamp-contacting terminal of the other socket. Still further and also more detailed objects will appear from the following specification and from the accompanying drawings, in which

Fig. 1 is a side elevation showing a socket, lamp and plug assembly embodying my invention.

Fig. 2 is a perspective view of the same with the lamps and the wire-terminal plug detached.

Fig. 3 is a fragmentary plan view of the same embodiment.

Fig. 4 is a section through the same embodiment taken along the line 4-4 of Figs. 1 or 3.

Fig. 5 is a transverse central and transverse section taken along the lines 5-5 of Figs. 2 and 4 and showing the assembly with the wire-terminal plug in its attached position, but with both lamps detached.

Fig. 6 is a fragmentary perspective view of the metal plate which constitutes one of the main portions of the upper lamp socket.

Fig. 7 is a bottom view of the metal conducting member of the upper lamp socket, and

Fig. 8 is a side elevation of the same taken from the left hand of Fig. 7.

Fig. 9 is a fragmentary section taken through Fig. 5 along the line 9-9 of that figure to show the connection between one current-receiving member of the lower lamp socket and the insulated contact member of the upper lamp socket.

In one of its commercial applications, my invention is particularly adapted for embodiment in two-light lamps as employed for affording both the continuously burning tail light of an automobile and the intermittently lighted stop signal, as for instance a lamp of the general type disclosed in my copending application No. 653,105, filed

July 23rd, 1923, on a combination tail and stop lamp. I am therefore illustrating various features of my invention in an embodiment particularly suited for such uses, although I do not wish to be limited to the employment of my invention in connection with any particular type of lamp or for any particular purpose.

Where a series of separately controlled lights are employed on a vehicle, it has been customary for many years to ground one side of each circuit and to employ only a single wire for making the other circuit connection to a socket, the connection from this ungrounded wire to the lamp being made by a spring-pressed plunger insulated from the shell of the socket and engaging the axial terminal of the lamp. However, where two lamps are mounted in a single casing, the use of a separate wire-terminal plug with each socket increases both the cost of the complete lamp and the space occupied by the same. To avoid both of these objections, I equip one of the sockets so that it will cooperate with a two-wire terminal plug and provide such conducting means that the circuit connections afforded by the mere attaching of the plug will carry the current respectively to the axial terminals of the two lamps.

Thus, I desirably provide an assembly which holds both of the lamp sockets in a rigidly fixed relation and preferably arrange this assembly so as to afford a unit which can readily be attached to lamp casings of various types. For example, the drawings show this mounting as including a supporting member comprising a horizontal web 1 constructed integral with a depending vertical web 2, the latter having a rearwardly directed collar 3 formed upon the same. This collar 3 houses a medial portion of a socket shell 4 equipped at its forward end with bayonet slots 5 for receiving the anchoring pins 6 on the base of a lamp 7, the said shell also having at its rear end bayonet slots 7 for receiving the corresponding lateral pins 8 on a wire terminal plug 9 to which the two ungrounded circuit wires 10 and 11' are attached.

The socket shell 4 has mounted within it the usual insulating core or body 11 housing a metal cylinder 12 which in turn houses a compression spring 13 disposed between a forwardly projecting plunger 14 and a rearwardly projecting plunger 15. Instead of being disposed axially of the insulating body 11 and of the socket shell 4, this cylinder 12 extends at an angle to the axis of the shell, so that the tip of the forward plunger 14 is disposed substantially axially of the shell or in position for contacting with the usual axial terminal of the lamp 7, while the rearwardly projecting plunger 15 is disposed for engaging the wire terminal 16

carried by the attachable plug 9 and connected to one wire 11' of the circuit. By thus inclining the plunger-carrying cylinder 12 to the axis of the socket, I secure ample room for having the insulating body 10 carry a second cylinder 17 which desirably extends parallel to the axis of the socket shell at one side of the latter. This cylinder 17 houses a compression spring 18 which continuously urges a plunger 19 rearwardly of the socket and into engagement with the forward end of a wire terminal 20 also carried by the plug 9 and connected to the wire 10 of the other circuit.

For the companion or auxiliary socket I desirably employ a compact structure in which the lamp-holding parts are formed largely by punching operations upon the horizontal web 1. For this purpose, I am showing this plate 1 as provided with a cylindrical perforation 21 closely approximating the outside diameter of the base 22 of the companion lamp 23, this perforation being enlarged at two diametrically opposite points by recesses 24 through which the usual anchoring pins 25 on the lamp base 22 may enter. Then I also form from the plate 1 a pair of downwardly open pocket formations 26 into which the said anchoring pins 25 are adapted to snap when the lamp base 22 has been partially rotated after the pins have passed downwardly through the recesses 24.

Instead of employing a spring-pressed plunger construction for engaging the axial contact 27 of this upper lamp, I desirably employ a spring finger 28 formed upon a conducting member stamped from resilient sheet metal, which member desirably has one of its parts connected directly to the cylinder 17. For this purpose, I am here showing a conducting member comprising a ring portion 29 having a resilient finger 28 formed from one edge thereof and extending across the axis of the ring, and having at its opposite edge a depending finger 30 which extends through a correspondingly disposed bore in the socket shell 4 and into a suitable transverse perforation in the cylinder 17. The ring-shaped portion 29 of the said conducting member is disposed coaxially with the perforation 21 and is suitably insulated from the metal plate 1, as for example by lower bushings 32 and upper washers 33 housing the shanks of the rivets 34 by means of which the said ring-shaped portion 29 is secured to the web 1. The depending finger 30 is also insulated from the metal supporting member, as by an insulating plate 35 which bears flatwise against the vertical web 2 of the supporting member and which is clamped between the depending finger 30 and the said web. By concaaving the lower end of this insulating plate 35 to conform to a portion of the periphery 130

of the socket shell 4 and by having the upper end of the insulating plate abut against the bottom of the metal plate 1, as shown in Fig. 2, I can readily cause the said clamping to hold the insulating plate in proper operative position without employing any auxiliary fastening elements.

To secure an adequate conducting connection between the finger 30 and the cylinder 17, I desirably reduce the free end of this finger to a tapering portion 36 which affords a driving fit when inserted in the transverse bore 37 as formed in the cylinder 17, so that the mere assembling of these parts insures a firm and adequate electrical connection.

When the upper lamp has its base inserted and partially rotated as above described, the resiliency of the spring finger 28 which presses upwardly against the axial terminal 23 of the upper lamp holds the anchoring pins 25 interlocked with the arched formations 26, thus affording a secure supporting of the lamp in a compact and exceedingly simple structure. However, the lamp might tend to rock about the axis of the anchoring pins 25. To guard against such a rocking movement, particularly when the lamp assembly is subjected to jarring, I desirably draw a couple of upwardly extending guide flanges 38 from the metal out of which the plate 1 is formed, these guide flanges being concaved to correspond to the bore of the perforation 21 and being at portions of this perforation which are at right angles to the common axis of the arch formations 26.

With the socket assembly thus arranged, it will be obvious from Fig. 5 that the upper socket construction is exceedingly compact and has its grounded metal portion formed out of sheet metal integral with the vertical web 2 and the collar 3 through which the lower socket extends. Hence my said assembly permits of mounting the two lamps relatively close to each other. Furthermore, since the electrical connection to the axial terminal of the upper lamp is made directly from the plunger cylinder 17 by the single conducting member which forms an operative and permanently attached part of the upper socket, no wiring is required for making the cross connection between the sockets. Indeed, the only wiring required is that of securing the two circuit wires 10 and 11' to the corresponding wire terminals of the detachable plug by means of the usual lateral screws 39. So also, it will be obvious from the drawings that the assembly as pictured in Figs. 1 and 2 can readily be handled as a unit, being assembled in its entirety (either with or without attaching the lamps to the same) before attaching this assembly to a casing of any kind. Moreover, since relatively short guide flanges 38 are employed for preventing the upper lamp from

rocking, I can provide a mounting which will afford a relatively close spacing of the two lamps, thereby permitting the use of a casing of relatively small diameter.

However, while I have illustrated and described the various features of my invention as combined in a single embodiment, I do not wish to be limited to the joint use of all of these features. Neither do I wish to be limited to the particular details of the construction and arrangement here described, it being obvious that the same might be modified in many ways without departing either from the spirit of my invention or from the appended claims. Furthermore, I am here claiming the feature of my presented construction which include the sheet metal supporting member, these being embodied in my copending divisional patent application, filed July 1, 1924, on interconnected lamp sockets.

I claim as my invention:—

1. A twin-lamp socket including a base having a vertical and a horizontal part, a socket shell carried by the vertical part of the base, a conductor member in the socket, an insulating plate abutting the inner face of said vertical part and engaged at one end with the under face of the horizontal part of the base, said plate having its other end comfortably engaging the socket shell, means to support a lamp on the horizontal part of the base, and a conducting member of the same angularity as that of the base secured to said horizontal part of the base and having a part engaged with the insulating plate to clamp same in position and also having electrical contact with the first named conductor member, and with the lamp on the horizontal part of the base.

2. A twin-lamp socket including a substantially L-shaped base, means to support a lamp on one of the arms of the base, a lamp receiving shell on the other arm, a contact in the shell, a substantially L-shaped conductor plate having one end secured to the corresponding arm of the base and having said end underlying the first named arm and formed to engage the axial terminal of the first named lamp, the other end of said conductor plate extending into the shell and being engaged with the contact thereof, and a contact in the shell for the axial terminal of the lamp thereof.

3. In a twin-lamp socket, an angular support, a conductor plate conforming and secured to the under side of the support, a pair of lamp sockets carried by the respective arms of the support, a slotted conductor member in one lamp socket, one end of said plate being engaged in the slot of said member, the opposite end of the plate having a ring registering with and disposed below the other lamp socket and having a resilient tongue extending across the ring.

- and formed to directly engage the axial terminal of a lamp in the other socket, and a lamp terminal engaging conductor in the first named socket.
5. 4. In a twin-lamp socket, a base having a horizontal and a vertical part, a lamp socket carried by the vertical part of said base so as to dispose the lamp beneath the horizontal part, a lamp socket carried by the 10 horizontal part, a conductor member having a ring-like part secured to the under face of the horizontal part and having a contact tongue disposed diametrically across the open center of the ring and beneath the horizontal part to engage the lamp of the latter, said conductor member having a second contact part engaging the socket of the vertical part of the base, and means to insulate the conductor member from the base.
- 15 5. In a twin-lamp socket, a base having a horizontal and a vertical part, a lamp socket carried by the vertical part of said base so as to dispose the lamp beneath the horizontal part, a lamp socket carried by 20 the horizontal part, a conductor member

having a part secured to the under face of the horizontal part to engage the lamp of the latter, said conductor member having a second contact part engaging the socket of the vertical part of the base, and means to insulate the base and conductor member.

6. A twin-lamp socket including a substantially L-shaped base, means to support a lamp on one of the arms of the base, a lamp receiving shell on the other arm, a contact in the shell, a substantially L-shaped conductor plate having one end secured to the corresponding arm of the base and having said end underlying the first named arm and formed to engage the axial terminal 40 of the first named lamp, a conductor member in the shell, the other end of said conductor plate being of wedge-shape and wedgingly engaged in a slot provided therefor in the conductor member, and a contact 45 in the shell for the axial terminal of the lamp thereof.

Signed at Chicago, Illinois, July 16th, 1923.

EDWARD S. PRESTON.
